UNITED STATES PATENT OFFICE.

HECTOR P. MACLAGAN, OF OAK PARK, ILLINOIS, ASSIGNOR TO MCINTOSH ELECTRICAL CORPORATION, OF CHICAGO, ILLINOIS, A CORPORATION OF DELAWARE.

CLOCK-CONTROLLED SWITCH.

Application filed January 24, 1925. Serial No. 4,401.

My invention relates to an improved construction of devices for operation by a standard clock construction to in turn control the operation of an electric switch by which a desired electric circuit or circuits may be controlled.

By my invention any standard clock construction may be employed to constitute the timing element of the device, my improved devices may be attached to the clock movement without rebuilding it in any way, and the circuit control effected by my devices is positive and direct.

My improved switch construction, controlled as referred to by clock work, may be employed for a wide variety of uses where it is desired to operate an electric switch to control a corresponding electric circuit, at the end of any predetermined interval, for example for electric applications in electro-therapy, electric lighting, electric cooking, etc.

My invention will best be understood by reference to the accompanying drawings showing a preferred embodiment in which

Fig. 1 shows my construction in front elevation as applied to a standard clock movement,

Fig. 2 shows in a view similar to Fig. 1 and diagrammatically, the clock movement employed in Fig. 1,

Fig. 3 is a lower edge view of a part of the construction shown in Fig. 1, certain of the parts being shown in section to better illustrate the construction,

Fig. 4 shows in a view similar to Fig. 3 and to an enlarged scale the parts directly controlling the switch operation, and

Fig. 5 is a bottom view of the parts shown in Fig. 4.

Similar numerals refer to similar parts throughout the several views.

As shown in Fig. 1, the casing of a standard clock is indicated at 10, provided with the usual main staff 11 carrying a minute hand 12. In placing my devices on a clock of standard construction, the parts employed to drive the hour hand from the main staff are removed and a disk 13 is rigidly secured to the staff 11 below the face 14 of the clock. The face 14 may be the regular clock face, to indicate the position of the hand 12, and an additional set of figures may be applied thereto as indicated at 15 if desired, to indicate the number of minutes

that will elapse before the hand 12 reaches its twelve o'clock indication, or in other words the position marked zero from any desired setting.

As indicated in Fig. 4 the disk 13 is provided on its lower surface with a beveled face 16 extending nearly or quite to the outer edge of the disk, said disk being provided in its lower face with a counterbore 17 concentric with the axis of the staff 11. The counterbore 17 is provided to receive the upper end of a pin 18 carried by the end of a lever 19 located adjacent the staff 11.

As indicated in Fig. 5, the counterbore 17 communicates at one side with a groove 20 having its bottom wall substantially in the same plane as the bottom of the counterbore 17, which extends nearly to the outer edge of the disk 13, the width of this groove being slightly greater than the diameter of the pin 18.

As indicated in Fig. 1 the lever 19 is pivotally mounted at 21 on the casing 10 of the device and is connected by means of a spring 22 with the casing in a manner tending to move the pin 18 from the counterbore 17 through the groove 20, when the angular position of the groove permits. The spring 22 is of sufficient strength not only to move the lever 19, but also to move the parts connected with said lever and intended for actuation thereby. For any position of the disk 13 excepting that bringing the groove 20 into the path of travel of the pin 18, movement of the lever 19 under the action of the spring 22 is restrained by the engagement of the pin 18 with the cylindrical wall of the counterbore 17.

The bearing 21 of the lever 19 also constitutes the pivotal support of a switch blade 23, for which reason the pivotal support 21 is preferably mounted upon a block of insulating material 24 supported by the casing 10 of the device. In its closed position the switch blade 23 engages electric contacts 25 and 26 mounted on blocks of insulating material 27 and 28 respectively, which in turn are carried by the casing 10 of the device. Electric conductors 29 and 30 are connected with the contacts 25 and 26 to form a part of the electric circuit to be controlled by the device. When moved to its alternate position, the switch blade 23 is moved from engagement with the contacts 25 and 26 to interrupt electric connection between them, and

thus open the circuit controlled by the device. A spring 31 is connected at its ends with the lever 19 and the switch blade 23 in a manner tending to move the switch blade 23 around 5 to the right upon its pivotal support 21, if for any reason the lever 19 is first moved on said pivotal support in the same direction. A stop pin 32 is carried by the switch blade 23 for engagement by the lever 19 to prevent 10 movement of the lever 19 around to the left relatively to the switch blade 23 beyond the relation indicated in Fig. 1. The spring 31 is of considerably less strength than the spring 22. The switch blade 23 preferably 15 carries a second stop pin 33 to limit the amount of possible motion of the lever 19 around to the right relatively to the switch blade 23, from the relation of the parts indicated in Fig. 1, without positively moving 20 the switch blade 23 with it. The lever 19 has connected thereto a setting rod 34 extending through a guide post 35 carried by the casing 10 of the device, said setting rod having secured thereto at its outer end, a knob 36 for 25 convenience of operation.

As indicated in Fig. 2, the staff 11 may conveniently be part of an ordinary timing train, indicated diagrammatically to said figure, making one rotation in an hour.

30 The operation of my improved device is as follows:

Assuming that the switch 23 is in its open position, and that it is desired to set the device to maintain the circuit connected with the wires 29 and 30 in closed condition for a limited time, for example fifteen minutes, the staff 11 is turned to the position corresponding to the desired time interval, for example to the position shown in Fig. 1, 35 either by the regular devices forming a part of the standard clock work mechanism provided for setting the hands, or by turning the hand 12 itself. This moves the groove 20 from alignment with the path of travel of the pin 18, assuming that it may have been in alignment before setting the hand 12, and in any event prevents immediate release of the pin 18 when it is moved to its position to cause the closing of the electric circuit. With 40 the hand 12 in its set position, the knob 36 is moved to the left for the relation of the parts shown in Fig. 1, to move the rod 34 through the post 35 thus moving the lever 19 around to the left on its pivotal support 21 45 against the action of the spring 22. The lever 19 is preferably made of spring material, for example spring brass or spring steel, and is thin enough to permit a ready bending of the lever when the end of the pin 18 engages the beveled or conical surface 16 of the disk 13. This permits the pin 18 to spring around the projecting edge of the counterbore 17 when the knob 36 is moved to set the switching mechanism. The spring of the 50 lever 19 moves the pin 18 into the counterbore

17 as soon as said pin has cleared the edge of said counterbore, and the lever 19 is wide enough to maintain the parts in their set position indicated in Fig. 1 against the action of the spring 22.

At the same time that the lever 19 is moved as described by the setting operation, it moves the switch blade 23 around to the left on its pivotal support 21, due to the engagement between the lever 19 and the stop pin 75 32, the parts being so proportioned that the switch blade is moved to fully engage the contacts 25 and 26 at the same time that the pin 18 passes the edge of the counterbore 17 during the setting operation. The switch 80 blade 23 is thus held positively in its closed position until the predetermined interval of time has elapsed, for which the circuit through the wires 29 and 30 is to be maintained in closed condition. At the end of that 85 interval, by the rotation of the staff 11 and the disk 13, the groove 20 is brought into alignment with the path of travel of the pin 18, which is thus freed from restraint by the cylindrical wall of the counterbore 17. The 90 tension on the spring 22 thereupon moves the lever 19 away from the staff 11 until it engages the pin 33 carried by the switch blade 23, at the same time placing the spring 31 95 under tension.

The further action of the spring 22 then moves the switch blade from engagement with the contacts 25 and 26 and at the instant of release of the switch blade from the contacts, the spring 31 is effective to quickly move 100 the switch blade away from the contacts and in the same direction of motion as imparted to the lever 19 by the spring 22. Motion in this direction of the switch blade is limited by engagement of the stop pin 32 with the lever 19. Motion of the lever 19 under the action of the spring 22 may be limited in any convenient manner, for example by the engagement of the knob 36 with the post 35. The action 105 of the switch referred to, thus provides a 110 quick break at its contacts to save the contact portions from undesirable arcing.

My device above described is intended for use where an electric circuit is to be controlled for a comparatively short interval that may 115 be represented by one complete revolution (or nearly so) of a staff of a standard clock construction, for example the main staff, that is the staff making one complete rotation in an hour. It will be observed that the parts employed to control the closure of the desired circuit and the parts requiring to be attached to the standard clock construction, are simple in construction and readily attached to the clock, and that they are located entirely outside of the frame work of the clock, thus making them applicable to clock work of any standard construction. It will further be observed that on account of the staff 11 having 120 relatively slow motion in any event, that 125 130

a considerable amount of pressure may be produced between the pin 18 and the wall of the counterbore 17 without modifying the action of the timing train materially, and that therefore the spring 22 may be given considerable tension, thus insuring positive action of the switch mechanism when released by the timing train. It will be understood that I do not limit myself to the particular relation of the disk 13 to the staff 11, as it may be applied to the staff in either way that is most convenient; it will be understood that I do not limit myself to the particular form of switching mechanism employed, as any equivalent may be used in carrying out my invention. The particular requisite is that a member acted upon by a spring shall be employed, restrained substantially as described by a device carried by a clock staff, and that there shall be connection between the switch employed and said member, such that the switch is actuated by the spring when the member is freed from the restraint exercised by the operating device carried by the timing staff.

While I have shown my invention in the particular embodiment above described, it will be understood that I do not limit myself to this exact construction as I may employ equivalents known to the art at the time of the filing of this application without departing from the scope of the appended claims.

What I claim is:

1. In a time controlled switch, the combination of a staff, devices for rotating said staff at a predetermined rate, a first member carried by said staff and having a retaining portion and a releasing portion, a second member for engagement with and disengagement from said first member, a spring tending to move said second member from engagement with said first member, an electric switch, and connections between said switch and said second member actuating said switch by movement of said second member to its disengaged position, said first member comprising a disk having a counterbore constituting its retaining portion and a clearance slot from said counterbore constituting its releasing portion and said second member comprising a pivotally mounted lever having a projecting portion for engagement with said first member.

2. In a time controlled switch, the combination of a clock driven staff, a disk carried by said staff and having a counterbore and releasing groove, mechanism for engaging said counterbore including a spring tending to move said mechanism to its released position, an electric switch, and connections between said switch and said mechanism to open said switch upon release of said mechanism, said mechanism comprising a pivotally supported lever having a pin for engaging said counterbore.

3. In a time controlled switch, the combination of a clock driven staff, a disk carried by said staff and having a counterbore and releasing groove, mechanism for engaging said counterbore including a spring tending to move said mechanism to its released position, an electric switch, and connections between said switch and said mechanism to open said switch upon release of said mechanism, said mechanism comprising a pivotally supported lever having a pin for engaging said counterbore, and said connections including a spring imparting a quick-break opening movement to said switch upon release of said mechanism. 70

4. In a time controlled switch, the combination of a clock driven staff, a disk carried by said staff and having a counterbore and releasing groove, mechanism for engaging said counterbore including a spring tending to move said mechanism to its released position, a pivotally mounted switch blade, contacts for engagement by said blade, a spring connecting said blade and said mechanism for quickly moving said blade on its release from said contacts, said mechanism comprising a pivotally supported lever having a pin for engaging said counterbore, and stops for limiting relative movement between said lever and said blade. 85

5. In a time controlled switch, the combination of a clock driven staff, a disk carried by said staff and having a counterbore and releasing groove, mechanism for engaging said counterbore including a spring tending to move said mechanism to its released position, an electric switch, and connections between said switch and said mechanism to open said switch upon release of said mechanism, said mechanism comprising a pivotally supported lever having a pin for engaging said counterbore, said disk having an inclined surface adjacent its counterbore facilitating engagement between said counterbore and said mechanism, and said lever being of spring material permitting movement of said pin over said inclined surface in setting said lever and switch. 100

6. In a switching mechanism for attachment to a clockwork having a staff moving at a constant rate, the combination of a disk for attachment to said staff, said disk having a counterbore and a releasing groove, mechanism for engaging said counterbore including a spring tending to move said mechanism to its released position, an electric switch, and connections between said switch and said mechanism to open said switch upon release of said mechanism, said mechanism comprising a pivotally supported lever having a pin for engaging said counterbore. 115

7. In a switching mechanism for attachment to a clockwork having a staff moving at a constant rate, the combination of a disk 120

for attachment to said staff, said disk having a counterbore and a releasing groove, mechanism for engaging said counterbore including a spring tending to move said mechanism to its released position, an electric switch, and connections between said switch and said mechanism to open said switch upon release of said mechanism, said mechanism comprising a pivotally supported lever having a pin for engaging said counterbore, and said connections including a spring imparting a quick-break opening movement to said switch upon release of said mechanism.

8. In a switching mechanism for attachment to a clockwork having a staff moving at a constant rate, the combination of a disk for attachment to said staff, said disk having a counterbore and a releasing groove, mechanism for engaging said counterbore including a spring tending to move said mechanism to its released position, an electric switch, and connections between said switch and said mechanism to open said switch upon release of said mechanism, said mechanism comprising a pivotally supported lever hav-

ing a pin for engaging said counterbore, said disk having an inclined surface adjacent its counterbore facilitating engagement between said counterbore and said mechanism, and said lever being of spring material permitting movement of said pin over said inclined surface in setting said lever and switch.

9. In a time controlled switch, the combination of a staff rotatable at a predetermined rate, a rotary retaining member carried by said staff, an electric switch, a lever extending from said switch to operate it, and a spring tending to move said lever to actuate said switch, said lever having a rigid portion directly engaging said member and communicating the force of said spring directly to said member and holding said lever against the force of said spring, said member having a clearance at one point freeing said lever of restraint by said member.

In witness whereof, I hereunto subscribe my name this 9th day of January, A. D. 1925.

HECTOR P. MACLAGAN.
